UNITED STATES PATENT OFFICE.

FREDERICK T. KITT, OF SEATTLE, WASHINGTON, ASSIGNOR, BY MESNE ASSIGNMENTS, TO AMERICAN CAR AND FOUNDRY COMPANY, OF NEW YORK, N. Y., A CORPORATION OF NEW JERSEY.

ELECTRIC RIVET-HEATER.

1,374,453.

Specification of Letters Patent.

Patented Apr. 12, 1921.

Application filed August 26, 1919. Serial No. 319,983.

To all whom it may concern:

Be it known that I, FREDERICK T. KITT, a resident of Seattle, county of King, and State of Washington, have invented a new and useful Improvement in Electric Rivet-Heaters, of which the following is a full and complete description, reference being had to the accompanying drawing, forming a part of this specification.

10 My invention has for its object to provide a rivet heater having jaws adapted to receive rivets of different lengths when opened and closed by equal movements of a predetermined length. It further has for its 15 object to provide a rivet heater in which the opening and closing is brought about by a relative angular movement of the jaws. It further has for its object to provide a transformer rivet heater having a new and improved construction for securing the cooling of the transformer when in operation. It further has for its object to provide an efficient blast for assisting in such cooling. It further has for its object to provide a 25 means for securing better contact between the jaws and the rivet to be heated.

The following is a description of an embodiment of my invention, reference being had to the accompanying drawings, in 30 which,

Figure 1: shows a vertical section of my apparatus, on a plane parallel to the primary and secondary winding;

Fig. 2 is a front view of the apparatus;

35 Fig. 3 is a plan view of the same; and,

Fig. 4 is a sectional detail of the jaws holding the rivet while being heated.

Referring more particularly to the drawings, P represents the primary of a transformer, I the laminated iron magnetic circuit, and S a single-turn secondary placed around the primary and approximately surrounding the same, all shown in cross-section. The primary winding is composed of 40 a large number of turns of wire, the number depending on the voltage of the source of alternating current supply from which power is obtained. A regulating switch B is used in order to form convenient means, 45 whereby the heating of the rivets may be regulated by supplying a greater or smaller amount of power, as it is obvious that small rivets do not require as much power as larger ones, besides the voltage of the source

of supply may vary, which variation can be 55 compensated for by means of the switch B. L represents a number of conductors or leads which are tapped into the primary coils at certain points and brought out to the contacts c at the base of the switch B. 60 L''' represents a lever pivoted at P' which point is connected to a switch D by means of the conductor L'. LL is another conductor leading from the coil P to the line of source of alternating current supply L'', the other 65 side of the source of supply being connected, as shown in Fig. 3, to one point of the switch D. With the switch D in closed position, as shown, current will flow from one line L'' to the point P' and thence through lever L''' 70 to whichever contact c it is resting upon, and thence through coil P and conductor LL to the other side of the line L''. This current, as is well known, will set up a magnetic 75 flux in the iron core I, which will, in turn, induce an electromotive force into the secondary S. This secondary is made up of as many units as is desirable, each unit being adapted to hold a rivet while the same is being heated, and is preferably made up 80 of two or more pieces of copper bars bent so as to approximately encircle the primary B and welded at the points W to cast or forged copper jaws J and J'. A represents two 85 straps of copper or other suitable material also welded to the secondary, the purpose of which is to hold all the units together firmly and to form a means of fastening the entire assembly of secondary members to the metal frame F, which, together with F', forms the 90 supports between which the iron core of the transformer is clamped. It will be noted that the secondary is fastened or suspended only at this point, which is an important feature as will be pointed out later. 95

The rivet R, which it is desired to heat, is placed between the jaws J, J', as shown, thus completing the secondary circuit and allowing a large volume of current at a very low voltage to flow, which quickly heats the rivet 100 to the temperature necessary for driving the same. A rod H is connected to the jaw J, as shown, and extends down through an insulating block F'' which rests upon the frame F, as shown in Fig. 2. Between this 105 block F'' and the enlarged upper portion of H, forming an abutment, is a strong compression spring E, which tends to force the

jaw J toward the jaw J'. The rod H extends to a convenient foot lever, which I have not deemed it necessary to show. In placing the rivet into the jaws to be heated, 5 the foot lever is pressed down, overcoming the tension of the spring E and forcing the jaws apart and the rivet is then placed as shown and the foot lever released, which causes a pressure to be placed upon the rivet, securing good contact between its ends and the copper jaws J, J'.

When the rivet has been sufficiently heated it is removed by again depressing the foot lever, which releases the tension, breaks the 15 electrical contact and enables the operator to lift the rivet out with his tongs.

It will be obvious to any one skilled in the art that a very large amperage is required to heat a rivet, also that the handling of so 20 large a volume of current makes it necessary that every possible resistance to its flow be eliminated in order that practically all the power will be expended in heating the rivet instead of heating other parts of the circuit. 25 It is also well known that joints or bolted connections which must carry a heavy current at a low voltage are very troublesome on account of their high resistance, and for that reason I have eliminated everything of 30 that nature in the secondary, and in order that different lengths of rivets may be heated without making it necessary to make mechanical adjustments, I have developed what might be termed "alligator" jaws, as shown, 35 the same consisting of two elongated jaws whose outer ends are spaced farther apart than their inner ends. In the construction shown the inner surfaces of the jaws are at an acute angle to one another and their relative movement is somewhat angular. 40

With this form of jaw or electrode any size of rivet may be heated, within the limits for which the particular machine is designed, by simply placing it within the jaws 45 as far as it will go, the opening and closing of the jaws for any size of rivet requiring movements of an equal predetermined length. A long rivet will be placed near the outer ends of the jaws, while a shorter one 50 will be placed farther in toward the throat. One of the jaws, preferably the lower one, is horizontal while the other extends out at an acute angle, as shown.

If the faces of these jaws were both flat 55 it is obvious that the upper end of the rivet would be in contact with the electrode on one side only, which would cause the rivet to heat unevenly as the greatest heat is at the contact surface. In order to eliminate this 60 objection, I have made the upper jaw in the form of an inverted V, as shown at J' in Fig. 4, which represents a cross-section taken on the line 4 in Fig. 1. It will be noticed that no matter how great the angle is between the jaws, the upper one will make con-

tact at two points on the rivet R, namely at h and h'. This is due to the fact that the opposing surfaces of the two electrodes or jaws approach each other on both sides of a vertical plane passing through the longitudinal axes of said two electrodes. 70

The object of holding the secondary to the frame F is two-fold: First, it forms a single point of suspension and enables the secondary to gradually bend from point A to the 75 jaw J when the foot lever is pressed down, making any joint or hinge unnecessary; second, it provides a means of conducting the heat of the secondary to the frame of the machine through which it is dissipated by a 80 natural ventilation and enables it to be spaced from the primary.

In order to prevent overheating of the primary B, I have provided an air space between the primary and secondary, which 85 makes a water-cooling system unnecessary. Under ordinary conditions, the natural radiation is sufficient, but under extra hard service conditions it may be necessary to stimulate the radiation, and for that purpose I have provided an air nozzle C consisting of a pipe affixed to the frame F approximately in the position shown, adjacent to the throat of the jaws and connected to a source of compressed air or a blower. 90 On the lower surface of this pipe C I provide a series of holes or a slot through which a volume of air can be forced between the primary and secondary, which will take the course indicated by the arrows. 100 The air when first ejected flows downward and then to the rear, whereupon, having become heated, it rises through the succeeding vertical portion of the passage, then passes forward and is discharged from the throat 105 between the jaws. This, together with the natural radiation as above mentioned, has proven ample for any conditions met with in practice.

The advantages of heating rivets by this 110 method is great efficiency and consequently very greatly reduced cost, the absence of any harmful gases given off by an open flame and the elimination of dirt and ashes, all of which is a great consideration, especially aboard ships either building or being 115 repaired. The lesser risk of fire is also a great advantage, especially on boats or in other places where riveting has to be done near inflammable substances.

As will be evident to those skilled in the art, my invention permits of various modifications without departing from the spirit thereof or the scope of the appended claims.

Having thus described my invention, what 125 I claim is:

1. In an electric rivet heater, the combination of a magnetic core, a primary winding upon the same, a secondary in inductive relation thereto, relatively movable ter- 130

5 minal jaws connected to said secondary, the opposing faces of the front ends of said jaws being farther separated than the inner portions thereof, and means for varying the distance between said jaws.

2. In an electric rivet heater, the combination of a magnetic core, a primary winding upon the same, a secondary in inductive relation thereto, terminal jaws connected to 10 said secondary capable of relative angular movement, the opposing faces of the front ends of said jaws being farther separated than the inner portions thereof, and means for varying the angle between said jaws.

3. In an electric rivet heater, the combination of electrodes for holding rivets and having V-surfaces in order to insure electrical contact at two points of the rivet end, as shown and described. 15

4. In an electric rivet heater, the combination of two electrodes having a relative movement and adapted to hold rivets, the opposing surfaces of said electrodes approaching one another on each side of a vertical plane passing through the longitudinal axes of said electrodes. 20 25
